CARL G. THOMPSON, OF ST. LOUIS, MISSOURI

AIRPLANE CONSTRUCTION

Application filed August 26, 1927. Serial No. 215,574.

My invention relates to improvements in airplane construction, and has among its main objects, to provide such a construction which shall be simple, convenient, sturdy, 5 quick-acting, reliable, render the control of the plane easier and safer, and to safeguard the occupants of the plane and persons in the vicinity of the plane.

The invention has among its other objects, 10 a construction of the kind described, in which a new wing will automatically move into operative position rapidly and effectively, to supplant a ruptured or broken wing, and thus maintain the equilibrium of the machine.

15 Another object of my invention is to provide a wing which will normally remain in inoperative position, but in the case of stoppage of the motor, or for other causes, may be extremely rapidly actuated into operative 20 position to supplement the lifting capacity of the other wings, and thus keep the machine in equilibrium and prevent a nose-dive or other such disaster.

Another object of my invention is to provide 25 a construction of the kind described, which will serve as a wind-break or baffle to retard the descent and forward movement of the machine whenever desired.

Many other objects and advantages of the 30 construction herein shown and described will be obvious to those skilled in the art to which this invention appertains, from the disclosures herein given.

To this end, my invention consists in the 35 novel construction, arrangement and combination of parts herein shown and described, and the uses mentioned, and more particularly pointed out in the claims.

In the drawings, wherein like reference 40 characters indicate like or corresponding parts throughout the views,

Figure 1 is a perspective view of a plane, showing my improvement thereon in inoperative, normal position;

45 Figure 2 is a top plan view of the auxiliary wing, showing the manner of control thereof;

Figure 3 is a fragmentary perspective view of one corner of the auxiliary wing;

50 Figure 4 is a side elevation, illustrating the various positions of adjustment thereof;

Figure 5 is a side elevation of the construction as used with a different type of airplane; and

Figure 6 is a detail showing the means for controlling the movement of the auxiliary 55 wing shown in Fig. 5.

It is well known that airplanes have not the desired safety or ease of control sufficient to render them popular for more general use, this being due, among other causes, to their 60 relatively delicate construction and balance, their employment of fragile material, etc., and in order to partially overcome these defects, I have provided a construction which will meet the need of safety and ease of control, and which withal, will be efficient and 65 practical.

In the drawings, A indicates an airplane of any preferred or desired construction, the same not forming a part of my invention, and 70 which in Figs. 1-4 inclusive is shown as a monoplane type, the same having the usual fuselage 1, one or more wings or planes 2, landing gear 3, propeller 4 and other equipment needless to enumerate. 75

The wing or plane 2, extending to each side of the fuselage, is of course, stationary or fixed in place, and there is shown superimposed thereon, one or more movable wings or planes 5, of improved construction, and 80 adapted to co-operate with or in lieu of the wings 2, in a manner to be more clearly hereinafter described. 85

The main or body portion of the wing 5 may be of any desired material such as canvas 85 or the like, and preferably reinforced throughout by means of wires or cordage or netting 6, the degree of curvature of the movable wing preferably being less than that of the stationary plane 2. 90

The forward and rear longitudinal edges of the wing 5 have relatively heavy rods 7 and 8 therealong, these rods being either solid or hollow, as desired, and the end edges of the wing have strips 9 thereat, to serve as clips or clamps, these strips preferably being of channel cross-section. 95

A series of means 10 interconnect the adjacent rear edges of the rigid and movable wings, each of these means preferably com- 100

prising a light wire or rod 11, pivotally connected at one end to the rear edge of the movable wing 5, said wire extending loosely through suitable apertures provided in the fixed wing, or through brackets thereon if desired, said wire having an enlargement 12 at its lower end to serve as a stop member to limit the separation of the two wings, in a manner to be more clearly hereinafter described. When the two wings are in the inoperative position shown in full lines, the wires of each of the elements will fall loosely through the apertures in the lower wing; and on separation of the wings the enlargement 12 will abut against the under side of the stationary plane to act as a stop.

The interconnections at the forward edges of the edges of the co-operating wings are somewhat different. At suitable distances 20 apart along the forward edge of the wing 2 are arranged brackets 13, these brackets preferably being in the shape of loops or keyways, with a restricted opening at the rear leading into an enlarged opening at the forward end 25 of the loop. Elements 14, preferably of light wires or rods, similar to the rear connecting elements 10, are preferably hingedly connected at their upper ends to the bar 7 of the wing 5. These elements extend forwardly 30 thereof and are thence hingedly interconnected to a cooperating section which extends downwardly, said latter sections having enlargements 15 at the lower ends. The elements 14 are much longer than the rear connecting elements 10, and intermediate the ends of each of the elements 14 is positioned a stop member 17, preferably of smaller diameter than the stop 15 and having the opposite ends tapered so as to be more readily 35 insertible through the enlarged openings of the brackets 13. In order to secure a better anchorage of the members 17 at the point desired, I prefer to form the element 14 out of two pieces of wire at said point, the adjacent 40 ends being interlooped, and then I cast the member 17 about the interlooped ends. The size of the stops 15 and 17 is such that when the elements 14 are in the position wherein the wing 5 is indicated as "a", the intermediate stops 17 will be at the reduced portions 45 of the slots through the bracket 13, to limit further separation of the co-operating wings, but, upon movement of the elements 14 outwardly or forwardly in the slot, the stops 50 17 will register with and may go upwardly through the enlarged ends of the loops, whereupon the enlargements 15 will then abut the under surface of the brackets to limit further separation.

55 In order to manually move the stops 17 to go through the brackets, I have provided a slide member 19, suitably mounted along a rail 16 along the top side of the forward edge of the wing 2, said slide having a series of cams 20, therealong, one cam adjacent each

element 14. At one end, preferably the inner ends of the slide, there is arranged operating means 21, which may be a bell-crank arm as shown, and a spring 22 may be arranged at the opposite end of the slide in order to retrieve the latter after operation thereof. It is obvious that movement of the slide will cause the cams thereon to engage with the elements 14 to move them outwardly and permit the intermediate stops 17 to register with the enlarged openings at the forward ends of the brackets 13.

In operation, the auxiliary wing or plane serves a wide number of uses or functions, which will now be set out:

Firstly, in the event of a rupture or break in the covering of either of the two wings constituting the plane of the airplane, the rush of air through said break will instantaneously and automatically lift the movable wing from its first or normal position until the latter is in the position indicated in dotted lines in Fig. 4, this position being marked "a". In this position the stops 12 engage the under surface of the fixed wing. The stops 17, however, are in the inner or reduced portions of the brackets. In this position of separation between the two wings the auxiliary wing functions exactly as the stationary wing did, to thereby permit uninterrupted 95 passage of the machine to its destination.

Secondly, in order to avoid any of the serious consequences that so often follow as a result of stoppage of the motor while in mid-air, the auxiliary wings 5, 5 are simultaneously actuated into their next or second position, indicated as "a" in Figure 4, the position just described in the preceding paragraph, wherein they will act in the dual capacity of holding up the forward end of the machine and to a degree retarding the speed or velocity or speed of the plane in its descent or landing, as the movable wings have more curvature to them than the stationary plane. In order to manually give an initial lift to the wings 5, 5, any suitable means may be provided, and in the embodiment shown I provide a lever 23 suitably connected to the wing 2 at various points 24, said lever having a lever arm 25 intermediate its ends, and having another arm 26 at one end, so that upon oscillation of the lever, the arm 25 will lift or tilt the wing 5 to such an extent to permit the air to rush thereunder to complete the full tilting separation between the wings. The 110 controls for the arm 26, as well as those for the arm 21 of the slide, may lead to the operator by any suitable devices, as by cables, sheaves, etc.

Thirdly, in landing the airplane, not only 115 in forced landings, but at air-ports as well, it is desirable that such landings take place with the least amount of running of the machine on the field, or of taxiing as it is termed. In order to accomplish this, the pilot, in de-

scending, first places the movable wing in the position shown as "a", if not already in such position, and then shoves the slide 7 to release the stops 17, to thereby actuate the wing to the position shown as "b", this being the full separation between the wings. When the wings are in the position "b" called the third position, the auxiliary wings will act as an air-break or baffle, somewhat like a parachute, to bring the machine to a comparatively quick stop with but minimum taxiing, and thus facilitate landings.

From the foregoing description, it is obvious that I have provided an equipment that serves either as a relief wing or as an auxiliary wing, and in which the safety of the occupants of the machine and also of the landing fields will be greatly enhanced, and in which said equipment may be actuated and controlled to make landings simple, convenient, and within a short distance.

In Figs. 5 and 6 of the drawings, I have shown the auxiliary wing as applied to a different type of airplane, and in which the auxiliary wings are preferably mounted to the top plane 28. I have also shown means whereby the auxiliary wings may be moved from their operative to their inoperative position, while the machine is in flight.

For this purpose I have provided a shaft 29, suitably journaled at 30, to the lower plane 2', and at suitable points along the shaft 29 are spools 31, to which one end of cables 32 may be attached. The other ends of the cables 32 are connected to the forward edges of the auxiliary wing, and if desired these cables may pass over pulleys 33', fixed to the forward edge of the stationary plane 28. A hand wheel 33 may be placed adjacent the operator, one end of the cable 34 being connected to the hand wheel and the other end of the cable 34 being wound with several turns about the shaft 29 or about a spool thereon.

When the auxiliary wing is thus mounted on an airplane of this type, the cable 32 can be released upon leaving the ground, to thereby permit the auxiliary wing to move into its second position, to thereby provide additional lifting surface for the machine, and thus render a better start for the airplane. After the proper height has been reached, the auxiliary wing can be retrieved to its first or inoperative position so as to not slow down the flying speed of the machine.

Having thus described my invention, it is obvious that various immaterial modifications may be made in the same without departing from the spirit of my invention; hence I do not wish to be understood as limiting myself to the exact construction, arrangement and combination of parts herein shown and described, or uses mentioned, except as limited by the claims.

What I claim as new and desire to secure by Letters Patent is:—

1. The combination with an airplane having a stationary wing thereon, of an auxiliary wing movable vertically thereof and normally superimposed thereon, and means for controlling the movement of the latter, said means comprising elements interconnecting the front and rear edges of the two wings but permitting a predetermined amount of separation therebetween, means for initially tilting the forward edge of the auxiliary wing to permit wind to enter thereunder to lift the auxiliary wing, means at said elements for limiting the separation between the two wings after a predetermined separation therebetween, and means for actuating said last-mentioned means to increase the amount of separation at the forward edges of the wings.

2. The combination with an airplane having a stationary wing, of an auxiliary wing movable relative thereto and normally superimposed thereon, and means for controlling the movement of the latter, said means comprising element interconnecting only the front and rear edges respectively of the two wings but permitting a predetermined amount of separation between said front and rear edges of both wings.

3. The combination with an airplane having a stationary wing, of an auxiliary wing normally superimposed thereon and bodily movable vertically thereof, means at the front and rear edges of said wings for interconnecting them thereat and permit separation therebetween at both edges, and means operable in advance of the operation of said last-mentioned means for initially tilting the forward edge of the auxiliary wing to permit air to enter thereunder and lift the same.

4. In airplane construction, the combination with a stationary wing, of a secondary wing supported thereon and movable vertically thereto, connecting elements along the front and rear edges of said planes for connecting them and permit of a predetermined amount of vertical separation therebetween, means for tilting the forward edge of the auxiliary wing to permit wind to enter thereunder to lift the same a predetermined distance, means cooperable with said elements for limiting said separation after said initial tilt of the auxiliary wing, and means for releasing said last-mentioned means to permit an increased separation of said wings at the forward edges thereof.

CARL G. THOMPSON.
